L. GICLAS.
RAIN SPOUT OR CONDUCTING PIPE.
APPLICATION FILED NOV. 16, 1912.

1,071,411.

Patented Aug. 26, 1913.

UNITED STATES PATENT OFFICE.

LOUIS GICLAS, OF WASHINGTON, DISTRICT OF COLUMBIA.

RAIN-SPOUT OR CONDUCTING-PIPE.

1,071,411.

Specification of Letters Patent. Patented Aug. 26, 1913.

Application filed November 16, 1912. Serial No. 731,835.

To all whom it may concern:

Be it known that I, Louis GICLAS, citizen of the United States, residing at Washington, in the District of Columbia, have invented certain new and useful Improvements in Rain-Spouts or Conducting-Pipes, of which the following is a specification, reference being had therein to the accompanying drawing.

10 This invention relates to improvements in rain spouts or conducting pipes and has for its object the overcoming of the damaging results frequently encountered in seamed metal pipes which are incapable of substantial expansion and consequently burst or separate at the seam in cold weather, especially under freezing conditions. Heretofore, it has been the practice to form sheet metal rain pipes in round sections of substantial length joined along a longitudinal line by a non-expansive seam formed by interlocking folded portions of the sheet metal, and no provision having been made for substantial expansion of the piping circumferentially, the internal pressure under icy conditions bulge the pipe at the seams, either ripping the pipe along the seam or pulling the joint apart so that water subsequently escapes and runs down the outside 20 of the pipe and against the wall, it being the common practice to locate the pipe seam at the back of the pipe and adjacent to the wall.

25 My present invention comprehends the provision of a pipe provided with an expandible joint or seam permitting substantial enlargement of the pipe circumferentially under internal pressures; and the formation and arrangement of said safety joint or 30 seam so that even under unanticipated conditions tending to separate the joint or loosen the interlocked flanges, the internal construction of the pipe will tend to still conduct the water through the pipe rather 35 than tending to cause the escape of the water through any crevice or opening in the wall thereof.

The preferred embodiment of the invention comprises a spout or conducting pipe 50 made up of relatively short sections as compared to the practice in vogue, and the joining of the individual sections together along a diagonal line across the front thereof, the piping at the joint forming an internal bead 55 or ridge across the line of falling movement

of the water through the pipe, acting to cause the water to jump or flow across the joint rather than along the internal groove at the joint as is the case with a seam occupying a true vertical position; also the connecting of the pipe sections together so that the diagonal seams thereof will break joint to further overcome any tendency of the water in its course of flowing movement to follow the seam from section to section and 60 to prevent elongation of a cracked or opened seam; and the formation of the joint or seam so that the members constituting the joint may relatively separate or contract while maintaining a proper sealed relation there- 65 between, all as will more fully hereinafter appear.

I have illustrated in the accompanying drawings forming a part hereof a convenient embodiment of the invention, and the 70 details in the construction and arrangement will be apparent from an inspection of the same in connection with the specific description hereinafter contained.

In the drawings: Figure 1 is a front view 80 of the conducting pipe; Fig. 2 is a similar enlarged view of one of the pipe sections; Fig. 3 is an inside view of a section showing the seamed portion or joint thereof, and Figs. 4 and 5 are enlarged cross sectional 85 views of Fig. 2.

Referring now more specifically to the drawings wherein like reference characters designate corresponding parts in the several views, A represents a series of short-length 90 pipes of circular cross-section connected together by soldering or otherwise, at the meeting ends thereof, as indicated at B. By "short-length sections" I am speaking relatively with respect to the prior art, it having 95 been the practice for some time to make these pipe sections in lengths of say about ten feet, whereas, my invention contemplates the sections of approximately three feet in length.

Each section is formed with a longitudinal joint of an expandible character constituted by reversely bending over the edges of the sheet metal as at C and D to constitute flanges adapted to interlock, as clearly illustrated in the drawings. It is not intended 105 that the edges of the flanges or hook-like parts shall abut the closed or base portions c' d' but rather that there shall be a substantial space c'' d'' therebetween permit- 110

ting expansion and contraction of the joint members. Within the base portions of the hook-like edges I may interpose a packing E, preferably asbestos, to better seal the joint, and the purpose of the asbestos material being to resist any burning-out tendency under the heating of the ends or other portions of the pipe sections in the soldering operation. The joints or seams of the pipe sections are not arranged in a true vertical position but are disposed diagonally across the front of the pipe, my conception embracing the placing of the joint at the front of the pipe as distinguished from the back thereof as is usual to render the same more accessible in case of needed repair, etc. I also arrange the diagonal seams of the sections of pipe so that they break-joint in adjoining sections so that in case of any ripping or pulling apart of one section, the same will not have a tendency to carry on through the adjacent section but will be interrupted by the solid portion of such adjacent section bridging the end of the joint of the section connected thereto. The inner edge F of each pipe section which underlies and hooks into the outer edge G forms at the fold or bend H an inwardly projecting ridge or raised part with reference to the outer edge, and by reason of this formation, together with the diagonal positioning of the seam, the same crosses the normal path of falling movement of the water through the pipe and causes the latter to jump across the crevice or space at the seam, so that the water will continue its downward vertical course through the pipe, flowing constantly away from the joint, as is not the case where the joint is truly vertical and the water has the tendency to flow down and follow the crevice or groove at the joint. This feature is especially advantageous in instances where under freezing conditions the pipe is unduly expanded and the seam or joint tends to part, which, in a vertical arrangement of the same will permit the water to flow through the wall of the pipe to the outside of the same, whereas in the present instance, the inwardly projecting edge or ridge acts, as previously stated, to cause the water to jump across the seam and follow its expected course down through the pipe.

From the foregoing construction it will be appreciated that in a simple and cheap manner I have provided a rain spout or conducting pipe well adapted for its intended purposes, and possessing improved characteristics, as set forth, over similar piping heretofore disclosed in this art, while enabling easier assembling of the improved type of pipe with standard elbow constructions, and fittings.

I am aware that it has heretofore been attempted to provide expanding pipes but they have been of peculiar shapes in cross-

section, and otherwise rendering the same expensive of manufacture and assembling, in that correspondingly special fittings had to be furnished, but it has been the aim of the present improvements to keep as nearly as possible to the standard cylindrical pipe, capable of assemblage and association with other parts as is the prevailing practice.

My pipe sections are easily manufactured, it simply being necessary to either form the hook flanges at the edges of the sheet metal either before or after bending the same into the circular or tubular formation, then hooking the edges together with the elastic packing in place, and then simply twisting the pipe by engagement of the ends thereof and turning the same in opposite directions to dispose the seam or joint diagonally or obliquely with reference to the pipe, after which the joint is closed tight on a mandrel to insure its maintenance in the condition thus formed.

I claim:—

1. A rain spout of the character described composed of a plurality of relatively short sections connected together at their meeting ends, each section being composed of sheet metal having a flexible seam interlocked against separation disposed diagonally across one face of the same and located within the pipe section, each seam breaking-joint with the seam of the adjacent pipe sections.

2. A rain spout of the character described composed of a plurality of relatively short sections connected together at their meeting ends, each section being composed of sheet metal having a flexible seam interlocked against separation disposed diagonally of the same, each seam breaking-joint with the seam of the adjacent pipe sections, and a correspondingly inclined internal ridge at the diagonal seam, substantially as and for the purpose described.

3. A pipe section of the character described composed of sheet metal having hook shaped edges against separation freely interlocking and unobstructed at their bent portions to permit expansion and contraction of the section, said hook-shaped edges being located within the pipe section, and a flexible packing within the seam, substantially as and for the purpose described.

4. A pipe section of the character described composed of sheet metal having a seam of hook shaped freely interlocking edges, said seam being arranged diagonally across one face of the pipe section and within the pipe section, and the interlocking hook shaped members being unobstructed at their bent portions to permit expansion and contraction of the pipe sections.

5. A pipe section of the character described composed of sheet metal having a seam of hook shaped freely interlocking

- edges to prevent separation thereof, said seam being arranged diagonally across one face of the pipe section and within the pipe section, and the interlocking hook shaped members being unobstructed at their bent portions to permit expansion and contraction of the pipe section, and a packing within the seam, substantially as and for the purpose described.
- 10 6. A pipe section of the character described composed of sheet metal having a seam of hook shaped interlocking edges, said seam being arranged diagonally of the pipe section across one face of the pipe for approximately the length thereof, a correspondingly inclined ridge being formed internally of the pipe section and adjoining the seam thereof, substantially as and for the purpose described.
- 15 7. A pipe section of the character described, composed of sheet metal having a seam of hook shaped interlocking edges to prevent separation thereof, said seam being arranged diagonally of the pipe section, the interlocking hook shaped members being loosely associated to permit expansion and contraction of the pipe section and forming a correspondingly inclined ridge internally of the pipe section and adjoining the diagonal seam thereof, substantially as and for the purpose described.
- 20 8. A pipe section of the character described, composed of sheet metal having a seam of hook shaped interlocking edges to prevent separation thereof, said seam being arranged diagonally of the pipe section, the interlocking hook shaped members being loosely associated to permit expansion and contraction of the pipe section, and a packing within the joint or seam, the interlocking members forming a correspondingly inclined ridge internally of the pipe section and adjoining the diagonal seam thereof,

substantially as and for the purpose described.

9. A pipe section of the character described composed of sheet metal having a seam formed by freely interlocking hook-shaped edges to prevent separation thereof, and a packing abutting the edges of the interfitted hook-shaped portions normally preventing complete closing of the same when assembled and permitting subsequent expansion of the joint, the interlocking edges being located within the pipe section, substantially as and for the purpose described.

10. A rain spout of the character described comprising a tubular body having a flexible seam disposed diagonally substantially from end to end across one face of said body, said seam being constituted by loosely interlocking hook edges formed on the body, the overlapping portions of the body and the wall adjoining the same being continuously smooth to present no obstructions opposite the bent edges of the hook portions to permit expansion and contraction of the latter, substantially as and for the purpose described.

11. A rain spout of the character described comprising a tubular body having a flexible seam disposed diagonally of said body, said seam being constituted by loosely interlocking edge portions adapted to permit expansion of the body but preventing separation of the edges thereof, said interlocking edge portions being arranged within the body, substantially as described.

In testimony whereof I affix my signature in presence of two witnesses.

LOUIS GICLAS.
